CLAIM

The ornamental design for a “key matrix”, as shown and described.

DESCRIPTION

FIG. 1 is a front, top and right side perspective view of a key matrix showing our new design;
 FIG. 2 is a top elevational view thereof;
 FIG. 3 is a front plan view thereof;
 FIG. 4 is a right side view thereof;
 FIG. 5 is a left side view thereof; and,
 FIG. 6 is a rear plan view thereof.
